CLAIM

The ornamental design for an electric heating hair straightener, as shown and described.

DESCRIPTION

FIG. 1 is a front right perspective view of an electric heating hair straightener in accordance with the present invention; FIG. 2 is an exploded front right perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines in the figures show portions of the electric heating hair straightener and form no part of the claimed design.
